UNITED STATES PATENT OFFICE.

FRITZ-WAGNER, OF BERLIN-LICHTERFELDE, GERMANY.

BALANCED VALVE.

Application filed September 6, 1924, Serial No. 736,239, and in Germany December 31, 1923.

My invention relates to balanced valves of the type comprising a main and auxiliary valve, a counter-pressure chamber in the valve housing and a throttle operatively connected with the auxiliary valve so as to control, in conformity with the motion of the main valve, the passage through which live steam flows to the counter-pressure chamber.

It is an object of my invention to provide a valve of the kind described, in which hammering of the main valve and the auxiliary valve is prevented without resorting to the inconvenient expedient of providing a balancing piston.

15 To this end, I provide a second throttle in connection with the main valve by which throttle the admission of live steam to the area laid open by the main valve, when it is lifted from its seat, is so restricted that the impetus which the steam imparts to the main-valve in lifting it, becomes zero after the main valve has performed a comparatively short stroke.

20 In a preferred embodiment of my invention, this second throttle comprises a restricted passage between the wall of a cylinder in the valve housing and the main valve, through which passage the live steam flows to the seat of the main valve.

25 By the cooperation of these two throttles, hammering is effectively prevented and a balancing piston is eliminated.

Hammering in valves of the usual type is due to the fact that the admission of live steam to the seat of the main valve is unrestricted, so that the pressure it exerts on the main valve is practically equal to its initial pressure, and the main valve, which, at the time of lifting is practically relieved 30 from pressure, strikes the auxiliary valve with a heavy blow. When the auxiliary valve is closed, steam is trapped in the counter-pressure chamber, and live steam flows to said chamber through the clearance between the main valve and the valve casing, and pressure builds up gradually in said chamber and finally forces the main valve away from the auxiliary valve. This relieves the pressure in the counter-pressure chamber 35 and the live steam pressure on the lower face of the main valve again throws it against the auxiliary valve so that there is permanent hammering of the valves.

40 To overcome the tendency to hammer, it has been proposed to combine the said first throttle with a balancing piston at the main

valve which causes compression in the counter-pressure chamber in conformity with the motion of the main valve. This expedient prevents hammering, but, as mentioned, is not satisfactory as the diameter of the balancing piston is inconveniently large, and so the valve becomes correspondingly large, heavy, and expensive.

45 In my invention, hammering is prevented without this objectionable expedient.

To elucidate the invention I have shown in the accompanying drawing two illustrative forms. In these drawings:

50 Figs. 1 and 2 are vertical sections through two steam valves, and

Fig. 3 is a plan of the main valve used in either form.

55 In the construction illustrated, the valve casing or cylinder 1 has a cover 2, and encloses the main valve 3 one end of which forms a piston adapted to having a sliding fit in said cylinder. An auxiliary valve 4 is mounted in the main valve, and a counter-pressure chamber 5 is formed between the main valve and the cover. In the main valve 3 is disposed an annular member 6 through which projects the valve stem or shank 7, which is connected at its lower end with the auxiliary valve 4. This annular member is supported by ribs 8, and has a cavity or chamber 9, the bottom of which is separated from the counter-pressure chamber 5 by means of a bottom plate 10 snugly fitted about the valve shank 7. At the top, the chamber 9 is in communication with the counter-pressure chamber 5 by means of an annular passage 11 about the valve shank. Two tubes 12 connect the chamber 9 with the live steam chamber 13 of the valve. In 60 both forms the valve shank 7 is provided with an annular member for controlling the passage 11. In Fig. 1 this annular member or ring 14 projects downward through the bottom plate 10, and its diameter is slightly 65 smaller than the diameter of the opening 11. In Fig. 2, the ring 14^a upon the shank 7 is disposed within the chamber 9, and its diameter is larger than the diameter of opening 11. Below the main valve is a chamber 15 70 to which the steam header (not shown) is connected.

75 The drawings show the valve in closed condition in which there is present in the counter-pressure chamber 5, the same steam pressure as in the live steam chamber 13 of the valve, since these two chambers are in

communication with each other through the tubes 12 and the annular passage 11. This connection between the two chambers remains open even after opening of the auxiliary valve 4. The diameter of the auxiliary valve is such that the engine or engines, the pipe lines of which are connected to the header, will be started slowly by the live steam flowing to the chamber 15 from the chamber 13, through the tubes 12, the chamber 9, the clearance 11, the counter-pressure chamber 5, the cavity of the valve 3, and the auxiliary valve 4. The main valve is not yet balanced at this time but will become so when the auxiliary valve 4 is opened further until the upper surface of the shank ring 14 will enter the passage 11 and relatively rapidly shut off the supply of live steam from the chamber 13 to the counter-pressure chamber 5. By the throttling of the supply of live steam to the counter-pressure chamber 5, there will be caused immediately a rapid equalization of pressure between the counter-pressure chamber 5 and the chamber 15 of the valve. The main valve which is thus balanced will be moved upward from its closed position by the further opening stroke of the valve shank by the upper surface of the auxiliary valve 4 coming into contact with the lower surface of the plate 10 immediately after throttling the live steam supply in passage 11.

If the stem 7 is moved no further after the main valve 3 has been lifted from its seat, the following action takes place. As soon as the main valve 3 opens, live steam from the chamber 13 flows to the chamber 15 through the narrow clearance between the skirt of the main valve and the cylinder 16. The steam is intensely throttled in this clearance, but yet will be under a certain excess pressure when arriving below the main valve so that it is able to impel the main valve upwards with a certain acceleration, but its excess pressure becomes zero as soon as the width of the gap between the main valve and its seat exceeds the clearance between its skirt and the cylinder 16, and so no further upwardly directed pressure will be exerted on the main valve.

In fact, the upward motion of the main valve is terminated even at an earlier period because when the main valve is raised it moves clear from the top of the auxiliary valve 4 and, at the same time, the ring 14 permits live steam to flow to the counter pressure chamber 5 through the annular gap 11, and this live steam now exerts pressure on the upper face of the main valve 3 so that the main valve is not only arrested but is reversed until it has resumed its normal position on the auxiliary valve 4. This is effected without hammering as the live steam passage through the annular clearance 11 is throttled and finally closed by the

ring 14 and so the pressure on the upper face of the main valve is reduced to zero.

The area which the valve 3 lays open when it is lifted from its seat, is always considerably in excess of that of the clearance through which live steam is admitted to the main valve past its skirt and the cylinder 16 and so the quantity of steam which actually flows through the main valve is considerably below the quantity which might flow through the chamber 15.

This condition is the same for any opening of the main valve and so no sudden surges of pressure will act on the main valve.

The only condition under which the main valve might be lifted from its normal position on the top of the auxiliary valve is fluctuating steam consumption, for instance, in a reciprocating engine where surges of unusual magnitude occur. Such surges, however, will form only gradually and so the main valve will be set in motion gradually as well and will be returned immediately by the supply of live steam to the counter-pressure chamber which is effected as described.

For completely eliminating all oscillations of the main valve, the ring 14^a in Fig. 2 is shown so disposed upon the valve shank that it is located entirely within the chamber 9 and the bottom area of the chamber exceeds the cover area by the area of the annular passage 11. Also, the diameter of the ring 14^a in this embodiment is greater than the diameter of the annular passage 11. The steam escaping from the counter-pressure chamber after the opening of the auxiliary valve 4, will be replaced by steam supply from the live steam chamber 13 until the annular opening 11 is closed by ring 14^a, which now acts simultaneously as a shoulder for opening of the relieved main valve. The opening of the main valve is effected without impact, since its lower part is guided in the cylinder 16 as in the case of the valve of Fig. 1. Since the bottom area of the chamber 9 is greater than its cover area, the excess pressure generated in the chamber during relieving of the main valve, exerts a downwardly directed pressure upon the main valve. Accordingly, as soon as the main valve leaves its closed position, it is pressed downward upon the ring 14^a through excess pressure. At the same time, however, it is so connected with the valve shank that it must follow each one of the motions of the latter as if the connection were a mechanical one. The effective surface in the chamber must, of course, be so great that the excess pressure is greater than the sum of the opposing forces. When this condition is fulfilled, the main valve can no longer move of its own accord from its shoulder, and hammering of the main valve is impossible.

When the stem 7 is moved downwards, the main valve 3 will follow under its own weight. If it should lag by accident, the supply of live steam to the counter-pressure chamber 5 which would be set up immediately, would cause the main valve to return to its initial position immediately. When lifting the main valve from its seat, considerable resistance due to adhesion must be overcome, particularly in large valves. To overcome this resistance I preferably provide the main valve 3 with a differential balancing piston 17 as indicated in Fig. 2. Its diameter is only a few mm. larger than the smallest diameter of the main valve.

When, in a valve of this type, the ring 14^a restricts the passage 11 to such an extent that less steam flows to the counter-pressure chamber 5 than is discharged from said chamber through the auxiliary valve 4, the live steam in the chamber 13 exerts excess pressure on the differential piston 17 which pressure increases as the pressure in the chamber 5 decreases and causes the main valve 3 to open automatically before the passage 11 has been completely closed. This lifting motion of the main valve, however, is immediately arrested by the combined action of the throttle 14, or 14^a, and the clearance 30 in the cylinder 16, and the main valve is reversed but its motion is arrested when the passage 11 has been so restricted that only as much live steam enters the counter-pressure chamber 5 as is discharged from it through the auxiliary valve 4. The main valve is now permanently held in its intermediate or floating position as all forces acting on the main valve are completely balanced.

40 The conditions of equilibrium of the main valve are disturbed by any further displacement of the stem 7 as the ring 14^a, on upward motion of the stem, increases the throttling action on the live steam, and, on downward motion, decreases it. Under the action of the variations of pressure brought about in the counter-pressure chamber 5 the main valve follows the valve stem immediately and until it has assumed its new position of equilibrium.

50 In the construction illustrated in Fig. 1, the flow of the live steam to the counter-pressure chamber 5 is regulated by the throttle 14, its upper surface cooperating with the lower edge of the annular passage 11.

In Fig. 2 the regulation is effected by the cooperation of a beveled face on the throttle 14^a and a corresponding face in the top of the chamber 9.

60 It follows that the throttle may be varied but I desire it to be understood that the two constructions shown and described are not its only possibilities, nor do I desire to be limited to the specific construction of the second throttle, viz, the cylinder 16 with its

narrow clearance, as this also may be modified.

Having thus described my invention, what I claim as new and desire to secure by Letters Patent is:—

1. In a valve, the combination of a valve box having an inlet and an outlet, a main valve body made in an outer and an inner section, the inner section formed with a chamber having a removable bottom and communicating with said inlet, said valve box being formed with a chamber arranged so that pressure fluid confined therein tends to force the main valve body on its seat and communicating with said chamber of said inner section, an auxiliary valve body controlling the discharge from said chamber of the valve box, and means for operating said valve bodies comprising a stem passing through a bore of said removable bottom. 70 75 80 85

2. In a valve, the combination of a valve box having an inlet and an outlet, a main valve body made in an outer and an inner section, the inner section formed with a chamber communicating with said inlet, said valve box being formed with a chamber arranged so that pressure fluid confined therein tends to force the main valve body on its seat and communicating with said chamber of said inner section through a central opening made in the wall of said inner section, an auxiliary valve body controlling the discharge from said chamber of the valve box, and a valve stem connected with said auxiliary valve and passing through the chamber of said inner section and said central opening, and providing an annular passage with the wall of the opening through which the chamber of the inner section communicates with said chamber of the box, said valve stem carrying a collar in position for controlling said annular passage and having a diameter larger than the outer diameter of said annular passage, the area of the wall of the chamber surrounding said annular passage being smaller than the area of the wall of the chamber located opposite to the annular passage. 90 95 100 105 110

3. In a valve, the combination of a valve box having an inlet and an outlet, a main valve body made in an outer and an inner section, the inner section formed with a chamber communicating with said inlet, said valve box being formed with a chamber arranged so that pressure fluid confined therein tends to force the main valve body on its seat and communicating with said chamber of said inner section through a central opening made in the wall of said inner section, an auxiliary valve body controlling the discharge from said chamber of the valve box, and a valve stem connected with said auxiliary valve and passing through the chamber of said inner section and said central opening and providing an annular passage with 115 120 125 130

the wall of the opening through which the chamber of the inner section communicates with said chamber of the box, said valve stem carrying a collar in position for controlling 5 said annular passage and having a diameter larger than the outer diameter of said annular passage, the area of the wall of the chamber surrounding said annular passage being so much smaller than the area of the wall of 10 the chamber located opposite to the annular passage that when the main valve body is removed from its seat the differential fluid pressure acting on said walls is sufficient to hold the main valve body on said collar.

15 4. In a valve, the combination of a valve casing having an inlet and an outlet, a main valve therein for controlling said outlet and cooperating with said casing to form a counter-pressure chamber, and said valve 20 having a chamber therein in open communication with said casing inlet, and a passage connecting said chambers, and said main valve also having an outlet from said counter-pressure chamber to the outlet of 25 the main casing, an auxiliary valve for controlling said main valve outlet, a valve stem for said auxiliary valve, and a throttling member on said stem in said second mentioned chamber, and of smaller diameter 30 than said chamber, said throttling device co-

operating with the end wall of said second mentioned chamber to restrict communication through said passage upon opening the auxiliary valve, and serving to close said passage and engage with said main valve to 35 open the latter upon further movement of the auxiliary valve.

5. A balanced valve comprising a cylinder having an annular seat at one end, an outlet beyond said seat and an inlet in the peripheral wall, and spaced from said seat, a main valve defining an interstice between itself and said cylinder intermediate said seat and said inlet, a piston part having a sliding fit in said cylinder at the opposite 40 side of said inlet, said piston part having a passage therethrough establishing communication between said inlet and said cylinder at the end thereof opposite to said seat, an auxiliary valve seating in said main valve 45 and controlling communication between said last mentioned cylinder end and said outlet, and means connected with said auxiliary valve for restricting the area of said passage in accordance with the relative displacement 50 of said main and auxiliary valves.

Signed at Berlin in the county of Brandenburg and State of Prussia, this 12th day of August A. D. 1924.

FRITZ WAGNER.
